UNITED STATES PATENT OFFICE.

DOX W. CARR, OF GREELEY, COLORADO, ASSIGNOR TO THE GREELEY MANUFACTURING COMPANY, OF GREELEY, COLORADO, A CORPORATION OF COLORADO.

DUMP-BED FOR VEHICLES.

980,922.

Specification of Letters Patent. Patented Jan. 10, 1911.

Application filed September 14, 1909. Serial No. 517,615.

To all whom it may concern:

Be it known that I, Dox W. CARR, a citizen of the United States, residing at Greeley, county of Weld, and State of Colorado, have invented certain new and useful Improvements in Dump-Beds for Vehicles; and I do declare the following to be a full, clear, and exact description of the invention, such as will enable others skilled in the art to which it appertains to make and use the same, reference being had to the accompanying drawings, which form a part of this specification.

My invention relates to improvements in dump beds for vehicles and may be considered an improvement over the constructions set forth in my previous applications, serially numbered 413,522 and 470,686, respectively.

My present invention relates particularly to the means for locking the vehicle body in the horizontal position, whereby it is prevented from tilting in either direction. In the construction illustrated in the drawing, an operating shaft is employed provided with a worm which engages a worm wheel mounted on a shaft carrying two cone-shaped operating drums with which are respectively connected operating cables which engage guide pulleys intermediate the drums and the opposite edges of the wagon body, with which the cables are connected for tilting the wagon body in either direction as the worm shaft is operated.

My improvement consists in providing a pair of bars at each extremity of the vehicle. Each pair of bars has two extremities pivotally connected with the stationary framework of the vehicle, while their other extremities are pivotally connected with the dumping body on opposite sides of the center. The two members of each pair of locking bars cross each other when the dumping body is in the horizontal position, one of the bars being provided with a recess which is engaged by the other bar, thus serving to lock the body of the vehicle in the said position. One bar of each pair has one of its extremities engaged by a spring which, when the bar is in alignment with the recess of its companion bar, causes the one bar to slip into the recess of the other, and maintains the actuated bar in the locking relation. When it is desired to dump the bed or wagon body, means are employed for moving the spring-actuated

bars against their springs sufficiently to disengage them from the recesses of their companion bars, and while the spring-actuated bars are held in their disengaged position, the operator turns the worm shaft, which quickly tilts the dumping bed sufficiently to throw the locking bars into such relation as to prevent the spring-actuated bars from returning to the locking position until the dumping bed is again restored.

Having briefly outlined my improved construction, I will proceed to describe the same in detail, reference being made to the accompanying drawings in which is illustrated an embodiment thereof.

In these drawings: Figure 1 is an underneath view of a vehicle body, equipped with my improvements. Fig. 2 is a cross section taken on the line 2—3, Fig. 1, looking toward the left, the dumping body being in the horizontal position. Fig. 3 is a similar section, showing the dumping body in the tilted or dumping position. Fig. 4 is a detail view showing the two pairs of locking arms in connection with the mechanism for disconnecting the spring-actuated member of each pair from its companion arm, the parts being shown on a larger scale than in the other views. Fig. 5 is a sectional detail view, the section being taken on the line 5—5, Fig. 2, the parts being shown on a larger scale. Fig. 6 is a rear end elevation of a vehicle equipped with my improvements.

The same reference characters indicate the same parts in all the views.

Let the numeral 5 designate the stationary framework of the vehicle, in which is journaled a shaft 6, carrying cone-shaped drums 7, having spiral grooves 8, engaged by cables 9, which engage guide pulleys 10 and 12, mounted on the frame, the extremities of the cables remote from their winding drums being connected with the body of the vehicle on opposite sides, as shown at 13. The shaft 6 is provided with a worm wheel (not shown) which is engaged by a worm 14, on the operating shaft 15, provided with a hand crank 16. By turning this shaft 15, the dumping body may be tilted in either direction.

As heretofore stated, the function of locking the dumping body in the horizontal position is preferably accomplished by two pairs of locking arms which are substan-

tially alike, one pair being located at each end of the vehicle. A description of one pair of these arms is therefore sufficient. Let the numerals 17 and 18 respectively designate the individual arms of each pair. The lower extremities of the two arms are pivotally connected with the stationary framework 5, as shown at 19 and 20, while their opposite extremities are pivotally connected with the dumping body 21 on opposite sides of the center, as shown at 22 and 22^A, which in this case designate pivot bolts. Each arm 18 is provided with a central recess 23, adapted to receive the central portion of the arm 17, when the dump bed is in the horizontal position. The extremity of each arm 17, which is connected with the bolt 22, is acted on by a coil spring 24, one extremity of which engages the arm 17, while the other extremity bears against an angle bracket 25, connected with the dumping body, as shown at 26. This bracket is connected with the pivot bolt 22, upon which the extremity of the arm 17 is free to move, the bolt-engaging extremity of the arm being provided with a slot 27. The spring 24 is so located as to press the arm 17 toward its companion arm 18, so that when the two arms are in the proper position, the one will engage the recess 23 of the other. Each arm 17 is composed of spring metal, and while its extremity opposite that engaged by the spring 24, may be secured tightly to the stationary framework, the arm nevertheless has sufficient yielding capacity to allow it to engage and disengage the recess 23 of its companion bar. It is evident, however, that the extremity of the bar which engages the stationary framework may, if desired, be so connected therewith as to permit a sufficient oscillating movement to enable it to perform the aforesaid function, even if the arm were non-yielding. It is, however, preferred to employ an arm composed of spring metal and to secure the extremity connected with the stationary framework tightly to the latter, since in this event the resilience of the arm will aid the coil spring in forcing the arm 17 quickly into the recess 23 of the other arm, when the two arms are in the proper relative position. The upper extremity of the arm 18 is slotted, as shown at 28, and the bolt 22^A passes through this slot and also through a bracket 29 between which and a plate 30, the extremity of the arm is located, the plate 30 being made fast to a bar 31 of the dumping body.

Fulcrumed on the rear end of the dump bed, as shown at 31^A, is a lever 32. A pin 33 is connected with this lever on one side of the fulcrum, as shown at 34, while a rod 35 is connected with the lever on the opposite side of the fulcrum, as shown at 36. The pin 33 passes through an opening 37, formed

in the bar 31 of the dumping body and has an expanded head 38, which engages the arm 17 of the rearwardly located pair of locking arms; while the extremity of the rod 35, opposite that connected with the lever is connected with the forwardly-located arm 17, as shown at 39. By virtue of its connection, when the lever 32 is thrown to the dotted line position (see Fig. 4), the two arms 17 are also thrown to the dotted line positions in the same figure, whereby they are disengaged from the recesses 23 of their companion arms; and while the lever is held by one hand in the dotted line position, the hand crank 16, connected with the worm shaft 15, is turned with the other hand until the dumping body is moved sufficiently to prevent the arms 17 from reengaging the recesses 23 of their companion arms. The lever may then be released, after which the tilting operation is continued. After the contents of the vehicle body have been dumped, the latter is returned to the horizontal position by reversing the rotation of the worm shaft, and as soon as the bed is restored, the arms 17, acting under the influence of the coil springs 24, and their own resilience, reengage recesses 23 of their companion arms.

Having thus described my invention, what I claim is:

1. The combination with a stationary framework and a dumping body, of means for locking the body in the horizontal position, comprising a pair of coöperating arms arranged to cross each other, the upper extremities of the arms being pivotally connected with the body, while their lower extremities are pivotally connected with the stationary framework, one of the said arms being provided with a recess adapted to receive the other arm, whereby the two arms are constructed to interlock when the body is in a horizontal position, one of the arms being spring-actuated for the purpose.

2. The combination with a stationary framework and a vehicle body tiltably mounted thereon, of means for retaining the vehicle body in the horizontal position, comprising a pair of coöperating, interlocking arms arranged to cross each other, one extremity of each arm being pivotally connected with the stationary framework, while its opposite extremity is pivotally connected with the body of the vehicle, one of the said arms being provided with a recess which the other arm is adapted to engage, when the vehicle body is properly adjusted, one of the said arms being spring-actuated for the purpose set forth.

3. In mechanism of the class described, the combination with a stationary framework and a body mounted thereon to tilt transversely, of a number of pairs of coöperating arms arranged to cross each other, one arm

of each pair being provided with a recess, and the other arm being spring-actuated to interlock with the recessed arm when in a predetermined position, one extremity of each arm of each pair being pivotally connected with the stationary framework, while their opposite extremities are pivotally connected with the tiltable body.

4. The combination with a stationary framework and a body tiltably mounted thereon, of means for locking the body in a predetermined position, comprising a pair of coöperating arms arranged to cross each other, one of the arms being provided with a centrally located recess, while the other arm is spring-actuated to interlock with the recessed arm when the two arms have assumed the desired position, the opposite extremities of the individual arms being pivotally connected with the framework and with the tiltable body, respectively.

5. The combination with a stationary framework and a body tiltably mounted thereon, of a pair of coöperating arms arranged to cross each other, one of the arms being recessed and the other spring-actuated to interlock with the recessed arm when in a predetermined position of adjustment, the opposite extremities of the individual arms being pivotally connected, respectively, with the stationary framework and the tiltable body.

6. The combination with a stationary framework and a body tiltably mounted thereon, of a pair of coöperating arms arranged to cross each other, one of the arms being recessed and the other spring-actuated to interlock with the recessed arm when in a predetermined position of adjustment, the opposite extremities of the individual arms being pivotally connected, respectively, with the stationary framework and the tiltable

body, and means for disengaging the spring-actuated arm from its coöperating arm, substantially as described.

7. The combination with a stationary framework and a body tiltably mounted thereon, of a pair of coöperating arms arranged to cross each other, one of the arms being recessed and the other spring-actuated to interlock with the recessed arm when in a predetermined position of adjustment, the opposite extremities of the individual arms being pivotally connected, respectively, with the stationary framework and the tiltable body, and means for disengaging the spring-actuated arm from its coöperating arm, comprising a lever and an operative connection between the lever and the spring actuated arm.

8. The combination with a stationary framework and a body tiltably mounted thereon, of means for locking the body in a predetermined position, comprising two pairs of coöperating arms arranged to cross each other, one arm of each pair being spring-actuated and the other provided with a recess to interlock with the spring-actuated arm, the opposite extremities of the individual arms of each pair being pivotally connected, respectively, with the stationary framework and the tiltable body, and means for disengaging the arms of each pair when in the interlocked position, comprising a lever connected in operative relation with the spring-actuated arms of each pair, substantially as described.

In testimony whereof I affix my signature in presence of two witnesses.
